(57) **CLAIM**

The ornamental design for a shelving sidewall as shown and described.

DESCRIPTION

FIG. 1 is a perspective view taken from a top, front, right side of a shelving sidewall according to a first embodiment of the design, the shelving sidewall being illustrated as installed in a shelving unit;

FIG. 2 is a perspective view taken from a top, front, left side of a mirror-image arrangement of the shelving sidewall according to the first embodiment of the design, the shelving sidewall being illustrated as installed in a shelving unit;

FIG. 3 is a top plan view of the shelving sidewall according to the first embodiment of the design;

FIG. 4 is a rear elevation view thereof;

FIG. 5 is a right side elevation view thereof;

FIG. 6 is a front elevation view thereof;

FIG. 7 is a left side elevation view thereof;

FIG. 8 is a bottom plan view thereof;

FIG. 9 is a perspective view taken from a top, front, right side of a shelving sidewall according to a second embodiment of the design, the shelving sidewall being illustrated as installed in a shelving unit;

FIG. 10 is a perspective view taken from a top, front, left side of a mirror-image arrangement of the shelving sidewall according to the second embodiment of the design, the shelving sidewall being illustrated as installed in a shelving unit;

FIG. 11 is a top plan view of the shelving sidewall according to the second embodiment of the design;

FIG. 12 is a rear elevation view thereof;

FIG. 13 is a right side elevation view thereof;

FIG. 14 is a left side elevation view thereof;

FIG. 15 is a front elevation view thereof; and,

FIG. 16 is a bottom plan view thereof.

Throughout the Figures, where shown, the dashed lines showing additional structure are for illustrative purposes only and form no part of the claimed design. The inventors anticipate that the claimed design can be any part, portion, element or combination of elements of the shelving sidewall shown in the figures.
